ERWIN KRAMER, OF BERLIN, GERMANY, ASSIGNOR TO HÄRTSTOFF-METALL AKTIEN-
GESELLSCHAFT (HAMETAG), OF BERLIN-COPENICK, GERMANY.

BOW TROLLEY FOR ELECTRIC VEHICLES.

Application filed November 7, 1925, Serial No. 67,546, and in Germany November 11, 1924.

My invention relates to sliding contacts adapted to slide along a conductor, such as an overhead wire, for the purpose of taking electric current therefrom, and conveying it to an electric car or the like. The invention relates and is more particularly applicable to bow collectors which are resiliently held in sliding contact with the trolley wire.

The objects of the present invention are to improve the electrical contact between such sliding collectors and the trolley wire, to reduce the wear on the bow and the wire and the formation of electric sparks, and to lessen the mechanical stresses on the overhead wire and the bow collector.

These objects I attain by reducing the weight of the sliding part of the bow collector to the greatest possible extent, which lessens the oscillations of the collector and its inertia and thus enables it to more readily adapt itself to the irregularities of the trolley wire.

Any unavoidable shocks that may be produced by vibrations of the car or overhead wire, or by defects in the latter, are thus rendered less serious, and the mechanical stress on the bow and trolley wire are reduced accordingly.

It is important to make the sliding member bear continually against the trolley wire also because it has been found that the sparking caused by this member when separating from said wire gives rise to considerable disturbances in radio broadcasting receiving sets, particularly when the spark current is small.

By the present invention the sliding action between the sliding member and the trolley wire is improved, for in the sliding member the lubricant required for lubricating the contact surfaces is uniformly distributed in the body of the metal so that no lubricant grooves liable to become inoperative are required, and no lubricant, need be applied to the overhead wire. The lubricant that is mixed with the metal of the sliding member preferably consists of graphite, soot or the like. In this way smooth contact surfaces are obtained, their wear and tear is reduced, and they therefore require less attention.

Another feature of the invention relates to the mechanical structure of the sliding member and its mounting upon the bow collector. The sliding member that contacts with, and takes the current from, the trolley wire is

made from fine metal powder well mixed with 55 10 to 20%, or more, of graphite powder. This mixture is pressed into the desired shape and converted into a coherent but porous body by heating. The production of sliding contacts from metal powder mixed with 60 graphite for other purposes has already been proposed, and it is also known that such sliding contacts are particularly adapted for obtaining sparkless running.

A novel effect is obtained, however, for the 65 purposes of the present invention which consists in the fact that in the manner described above a sliding member of low specific weight is obtained, which is lighter than that of the unmixed metal, and which, nevertheless, is 70 far superior to the unmixed metal in respect of its slipping and current taking effect. As the sliding member is arranged at the extreme end of the bow collector, it is particularly important to have it as light as possible, because at this part of the collector it 75 affects the inertia of the latter very considerably.

Because of the good metallic contact obtained with the novel sliding member, the 80 contacting surface of the same can be made smaller than in the known kinds of sliding members, so that it is capable of most accurately adapting itself to the unavoidable irregularities of the trolley wire and thus reducing 85 sparking from which the above mentioned evils arise. Smallness of the contacting surface has the additional effect of reducing the weight of the entire sliding member.

The metals whose powders are most suitable for producing the sliding member are those bearing a high degree of conductivity, such as copper, copper alloys, aluminum etc. and mixtures of these metals. Aluminum 90 is the most suitable for very light sliding members. By the use of aluminum powder mixed with graphite a porous body is obtained whose specific weight can be reduced 95 to 30% below that of rolled aluminum.

Any known method of making such bodies 100 of pressed metal and carbonaceous powders, with or without an admixture of binding agent, may be employed.

A manner of carrying out the invention is shown in the drawing in which Fig. 1 is a front view, partly in section, of a bow collector, Fig. 2 a sectional view of a corner of the bow collector and Fig. 3 a section, taken

at right angles to that of Fig. 2, of the sliding member bearing against a trolley wire.

To facilitate manufacture, the sliding member 1 is made of several parts or blocks.

- 5 For street cars or trans, where the bow collector 2 assumes an inclined position, the sliding blocks are made of the cross section shown in Fig. 3. The contacting sides 3 and 4 form an obtuse angle and are arranged so that the one side or the other bears along the whole of its length against the overhead wire 5 as shown according as the car travels in the one or the other direction. The two halves of the block at the two sides of the plane, indicated by the line A B and extending vertically to the surface of the drawing, are symmetrical and its external surfaces 6, 7 run parallel to the plane through A, B. The bottom surface 8 of the block may be made flat or curved. In the drawing it is shown flat and extends at right angles to the plane through A, B. In this bottom side 8 a groove with converging sides is made into which is fitted a rolled iron bar 9 of dove-tail section.
- 10 20 The individual blocks 1 are connected in this way by the rod 9. The ends 10 of the rod 9 are threaded as indicated in Fig. 2 and the blocks 1 are forced together laterally by screw nuts 11. The individual blocks 1 are thus forced into intimate contact and form a rigid unit with the rod 9. Projecting from the threaded sections 10 are pins 12 that fit into the ends of the bow 2 and are fixed in the same. When the rod 9 is taken out of the bow 2, the blocks 1 can be removed and replaced.
- 25 30 35

By shaping the cross section of the blocks as shown in Fig. 3, so that the sides 6 and 7 run parallel to each other, the amount of contacting surface bearing against the trolley wire is always maintained the same as the block wears down. The block may be worn down almost as far as the rod so that its material is utilized to the greatest possible extent. This feature is affected favorably by

the angle at which the surfaces 3 and 4 are placed to each other, as this requires the smallest possible quantity of block material for the arrangement of the rod 9, this quantity being indicated in Fig. 3 by the cross-hatched surfaces 13 and 14.

50 The sliding blocks may, of course, be fixed on the rod 9 in some other manner if desired. For example, a round rod may be used that is threaded through boreholes in the blocks 1. An advantage of the illustrated construction, 55 however, is that the blocks 1 are secured against rotation without the use of any special means therefor.

I claim:

1. In combination with a bow-collector for 60 street cars and the like, a sliding contact consisting of a porous body formed of powdered metal or metals of relatively light weight and graphite intimately and uniformly mixed therewith and compressed to the desired 65 shape.

2. In combination with a bow-collector for 70 street cars and the like, a sliding contact consisting of a porous body formed of powdered aluminum and graphite intimately and uniformly mixed therewith and compressed to the desired 75 shape.

3. In combination with a bow-collector for 80 street cars and the like, a sliding contact consisting of a porous body formed of light weight powdered metal, and graphite intimately and uniformly mixed therewith in amounts of 10 to 25% and compressed to the desired 85 shape.

4. In combination with a bow-collector for 80 street cars and the like, a sliding contact consisting of a porous body formed of relatively light weight powdered metal, and graphite intimately and uniformly mixed therewith and compressed to the desired shape, and a 85 stiffening member for said contact.

In testimony whereof I affix my signature.

ERWIN KRAMER.
